UNITED STATES PATENT OFFICE.

JOHN T. HALL, OF HACIENDA, TEXAS.

FOLDING COT.

1,334,091.

Specification of Letters Patent. Patented Mar. 16, 1920.

Application filed October 4, 1919. Serial No. 328,349.

To all whom it may concern:

Be it known that I, JOHN T. HALL, a citizen of the United States, residing at Hacienda, county of Uvaldo, State of Texas, 5 have invented certain new and useful Improvements in Folding Cots, of which the following is a specification.

My invention relates to folding cots, more particularly adapted for use in connection 10 with automobiles, though equally well adapted for use in other positions, and has for its object to provide certain improvements in the construction of the same as herein-after more definitely will be pointed out and 15 claimed, reference being had to the accompanying drawings, in which:

Figure 1 is a perspective view of my improved cot shown in open position.

Fig. 2 is a top plan view of the cot shown 20 substantially in knock-down or folded position, the legs at one end of the cot being omitted for the purpose of clearness of illustration.

Fig. 3 is a transverse sectional view, taken 25 along the line III—III of Fig. 4.

Fig. 4 is a side elevation, showing the upper end pieces of the device in folded position.

Fig. 5 is an enlarged detail perspective 30 view of one element of the side legs.

Fig. 6 is a similar view of the same part, taken at a different angle.

Fig. 7 is a similar view of the upper portion of the other element of the side legs.

Fig. 8 is a transverse section taken through 35 one of the side legs.

Fig. 9 is a detail sectional view, taken on the line IX—IX of Fig. 3.

Fig. 10 is a detail perspective view of one 40 of the diagonal sectional connecting bars, the parts being shown separated.

Fig. 11 is a plan view of one of the slats.

Fig. 12 is a side elevation of the same.

Similar numerals of reference denote 45 corresponding parts in the several views.

In the said drawings the reference numerals 1 denote the longitudinal side bars of the cot, the same being made preferably of wood. Fixed at each end of said bars 50 1 on their sides are metallic plates 2, formed with upstanding apertured lugs 3, between which lie similar apertured lugs formed on plates 4 fastened to the sides of the end pieces 5 of the cot, said plates 2 and 4 thus 55 forming hinge connections between said parts 1 and 5. By reference to Fig. 4 it

will be observed that the ends of the bars 1 are beveled at 6 and the inner ends of the end pieces 5 are similarly beveled at 7, whereby said end pieces 5 will, when opened, 60 be retained in an upwardly projecting angular position with respect to the bars 1, as shown in Fig. 1.

Pivoted to the inner sides of the bars 1, near each end of the latter, by means of 65 pivot bolts 8, are the heads 9 of the leg members 10, said leg members extending downwardly and being formed angular in cross sections, as shown in Figs. 5, 6 and 8. Extending from the heads 8 outwardly are 70 stops 11, adapted when the legs are in their open position to engage against the under surfaces of the bars 1 to limit the outward movement of said legs. This outward movement of the legs is also limited by the diagonal hinge bars 12 pivoted to said members 10 intermediate their length and to the side bars 1 at 13. Said members 10 are provided at their lower ends with angularly bent 75 clips 14, as shown in detail in Figs. 5 and 80 6, and adapted to interfit with said members 10 are the extension members 15, also angularly shaped to correspond with said members 10, and provided at their upper ends with bent clips 16, similar to the clips 14. 85 Said members 15 are formed near their upper ends into apertured ears 17 adapted to have pivoted thereto the ends of the cross bar 18, hereinafter described. Said members 15 are also formed just below the ears 90 17 into hubs 19, adapted to receive pins 20, which may be projected into any one of a series of holes 21 in the members 10, whereby the extension members 15 may be retained in any desired adjusted position vertically 95 with respect to the members 10, thus providing extension legs for the cot.

The legs at each end of the cot are provided with the upper cross bars 18 hinged to the members 15, as hereinbefore described, 100 and at their inner ends hinged to a plate 22, best seen in Fig. 3, said bars also having hinged thereto at their lower ends similar lower cross bars 23, in turn hinged at their outer ends to the members 15. Also hinged 105 to the bars 18 and 23 are the vertical bars 24, and hingedly connecting the lower ends of said bars 24 and the lower ends of the members 15 are the horizontal bars 25. In order to limit the opening movement of the 110 frame formed by the bars 18, 23, 24 and 25, I provide short diagonal bars 26 hinged

near the inner ends of the horizontal bars 23 and connected together at their upper ends by bolts 27 having vertical movement in slots 28 formed in the plates 22. As a further stiffening element I provide two-part brace bars 29, shown in detail in Fig. 10, the same being so constructed as shown, that they may fold in one direction only.

Referring to Fig. 9, it will be seen that the bars 25 are provided with shoes 30 of equal length therewith, and formed preferably of wood, said shoes having fixed to their side faces metallic plates 31 inturned at their upper ends to clip over the bars 25, as shown, said plates being adapted to slide outwardly on said bars 25, as shown in dotted lines in Fig. 3, whereby extension feet may be provided for the article, in a manner readily understood.

20 By referring to Fig. 4, it will be observed that the pivots 32 for the legs at the left end of the cot are disposed farther to one side of said legs than are the pivots 33 at the right end of the cot. By this construction 25 when the parts are brought to their folded position, the cot legs at the left end will assume a position shown in dotted lines in said Fig. 4 parallel with the folded end pieces 5, whereas the legs at the right end 30 of the cot will assume a position just below those at the left end and parallel with the side members 1, thereby providing an extremely compact structure when the device is folded.

35 In order to provide a bed bottom for the cot I employ a series of cross slats 34 fastened together by a suitable webbing 35, and properly to retain said bed bottom in position I provide a series of studs 36 on the 40 end pieces 5 adapted to engage in apertures 37 in said slats 34 in a manner readily understood. And in order that when folded the end pieces 5 may lie flush with the side bars 1, I provide a series of apertures 38 in the 45 top surfaces of said side bars to receive said studs 36, as shown in Fig. 3. I also provide one or more central studs 39 on the side bars 1, adapted to engage the central slat or slats, it having been found that this number of 50 fastening means is sufficient properly to retain the bed bottom in position.

It will be understood that a suitable mattress and bed covering will be used in connection with this cot, and it will also be understood that said cot is particularly well adapted for use in the interior of four-seated automobiles, due to the fact that there are no longitudinal braces or supports required for the legs, it being possible 55 through this construction to position the cot within an automobile just above its seat backs, the extension legs being capable of being projected to rest upon the floor of the automobile, and it will be apparent that 60 said cot is equally well adapted for use upon 65

the ground, the horizontally extendible feet affording a firm support wherever used.

Having thus described my invention, what I claim as new and desire to secure by Letters Patent, is:—

1. A folding cot, comprising side bars, leg members hinged to the ends of said side bars, and collapsible frames connecting said leg members transversely and comprising bottom members forming when in open position transverse horizontally disposed feet, 75 said frames when collapsed drawing said leg members and side bars toward each other and said bottom members upward.

2. A folding cot, comprising side bars, 80 leg members hinged to the ends of said side bars, and collapsible frame connecting said leg members transversely and comprising bottom members forming when in open position transverse horizontally disposed feet, 85 said frames when collapsed drawing said leg members and side bars toward each other and said bottom members upward and said frames and leg members adapted to fold bodily lengthwise of said side bars and be- 90 tween the latter.

3. A folding cot, comprising side bars, leg members hinged to the ends of said side bars, and collapsible frames connecting said leg members transversely and comprising 95 bottom members forming when in open position transverse horizontally disposed feet, said frames when collapsed drawing said leg members and side bars toward each other and said bottom members upward and said 100 frames and leg members adapted to fold bodily lengthwise of said side bars and be- 105 tween the latter, the legs and frames being so hinged to the side bars as to fold in parallel but different planes between said side bars.

4. A folding cot, comprising side bars, leg members hinged to the ends of said side bars, extension leg members slidably interfitting with said hinged leg members, and 110 collapsible frames connecting said extensible leg members transversely of the side bars.

5. A folding cot, comprising side bars, leg members hinged to the ends of said side bars, extension leg members interfitting with 115 said hinged leg members, collapsible frames connecting said extensible leg members transversely of the side bars, and laterally extensible shoes carried by the lower ends of said collapsible frames.

6. A folding cot, comprising side bars, leg members hinged to the ends of said side bars, extension leg members interfitting with said hinged members, collapsible frames connecting said extensible leg members trans- 125 versely of the side bars and comprising lower arms horizontally disposed when the cot is in an open position, and shoes slidable lengthwise of said lower arms and adapted to form laterally extensible feet. 130

7. A folding cot, comprising side bars, end pieces hinged to said side bars and adapted when unfolded to form extensions thereof, folding legs for supporting said side bars, a series of cross slats fastened together by webbing and adapted to rest upon said side bars and end pieces, and studs on said end pieces adapted detachably to engage

apertures in said cross bars to retain the latter in position, said side bars being provided 10 with a series of apertures to receive said studs when the latter are disposed in folded position thereon.

In testimony whereof I hereunto set my hand this 27th day of September, 1919.

JOHN T. HALL.
